UNITED STATES PATENT OFFICE

NICHOLAS MARCALUS, OF LYNBROOK, NEW YORK, ASSIGNOR TO AUTOMATIC PAPER MACHINERY CO., INC., A CORPORATION OF NEW JERSEY

WAX PAPER PACKAGE

Application filed February 7, 1929. Serial No. 338,143.

This invention relates to boxes or dispensing packages for rolls of paper, and has for its object to make certain improvements in the box described in my Patent No. 1,630,495.

- 5 That box is a relatively long card-board container designed to enclose a roll of paper, the free edge of the front wall being provided with a metal strip having a serrated cutting or tearing edge. The paper is drawn from 10 the roll while the latter is held in the box, and torn along the serrated edge when the desired length has been unrolled. During this operation the top of the box is preferably closed with its flap tucked behind the front wall, the 15 latter with the flap forming a guideway for the paper. In order to facilitate the unrolling of subsequent sheets the flap, the cover and the front wall below the metal strip are provided with openings enabling the user to 20 grasp the forward end of the paper with thumb and forefinger and thus start the unrolling operation.

In shipping such a box with its contained roll, the cover flap is placed outside and over 25 the serrated edge for the purpose of protecting the latter, and then some sealing means employed. Thus, when the user, commonly a housewife, receives the package it is not in readiness for use. She must break the seal, 30 open the box, withdraw a short length of paper and then insert the flap behind the paper which she has just withdrawn. This is a simple thing to do, it is true, but it would be preferable to sell the package with the 35 paper in position for immediate withdrawal. In accordance with the present invention the cover flap is placed behind the front wall at the factory and the forward end of the paper placed between the two so that the purchaser 40 perceives at once the manner in which the paper is to be withdrawn. As the package is thus shipped with the serrated metal edge exposed I place it for protection slightly below the plane of the cover when the latter is 45 in closed position. The ends of the cover are extended a fraction of an inch so that they overlie the ends when the cover is closed and thus make it difficult to depress the cover below the level of the serrated edge when the 50 paper roll no longer fills the box. As a fur-

ther protection for the cutting edge I prefer to fold the forward end of the paper down over the metal.

I have also invented improved means for holding the box closed during transportation 55 without the use of a seal. Instead of removing the card-board from the finger opening in the cover, I score in outline the part to be removed from the cover and provide the part to be removed from the flap with two laterally extending tongues which are inserted through the opening in the front wall and thus hold the cover snugly in place. It is then a simple matter to open the box, tear out 60 the tab or tuck piece and proceed to withdraw 65 the paper.

When the box is in use it is necessary that the cover remain closed with its flap behind the front wall of the box. After the removal of the tuck there is a tendency for the cover to spring open and remain so, making it necessary for the user to reinsert the flap behind the front wall whenever paper is to be withdrawn. In accordance with the present invention I therefore half cut the card-board 70 along the back end of the cover to minimize the spring of the cover and cause it to remain 75 closed.

In the accompanying drawings I have illustrated a preferred embodiment of my invention. In these drawings,

Figure 1 is a perspective view of a box made in accordance with the present invention, showing the box filled with paper and closed and ready for shipment;

Figure 2 is an enlarged sectional detail through the tuck taken along line 2—2 of Figure 1;

Figure 3 is a perspective view of the empty box with the cover in half open position;

Figure 4 is a fragmentary perspective of the box showing the tuck removed and the parts in position for dispensing paper;

Figure 5 is a transverse section taken along line 5—5 of Figure 4, and

Figure 6 is a sectional detail taken along line 6—6 of Figure 1 showing a projecting end of the cover.

The box illustrated is an elongated rectangular card-board box substantially square 100

in cross-section and designed to hold a roll of paper, such as a roll of waxed paper, commonly used by housewives for wrapping food. The front wall 1 of this box is provided along its upper edge with a metallic strip 2 having a serrated cutting edge 3. The upper edge of the front wall 1 is slightly below the level of the top of the box and the serrated cutting edge 3 also terminates just below the level of the cover 4, so that when the box is closed, as illustrated in Figures 4 and 6, the cutting edge does not project above the top of the box. When the box holds a complete roll, the roll itself may prevent the cover from being pushed down below the cutting edge, but as the paper is unrolled this is no longer true, and I therefore extend the ends of the cover, as at 5, so that they project slightly beyond the ends of the box, as illustrated most clearly in Figure 6. These projecting ends normally keep the cover above the cutting edge and therefore protect it during shipment, and also make it unlikely that the user of the box shall be scratched by the metallic points of the cutting edge.

The cover is provided with a downwardly extending flap 6 designed to lie behind the front wall during use, the flap and the front wall constituting a guide for the paper 7. In order that the package may be shipped with the parts in operative relation, I cut from the flap a tab, or tuck 8, provided with laterally extending tongues 9. The middle of the front wall of the box is provided, just below the metallic strip 2, with an opening 10 which serves the same function as the corresponding opening illustrated in the box of my Patent No. 1,630,495, namely to enable the user to initiate the withdrawal of the first sheet by inserting his thumb through this opening. A corresponding opening for the forefinger in the cover and flap is also necessary. The hole in the flap, left by the cutting out of the tuck 8, can serve the purpose of the opening in the flap and the opening in the cover is obtained by scoring a section 11 immediately adjacent the tuck.

To prepare the package for shipment the roll is placed in the box in the position illustrated in Figures 2 and 5, and the forward edge drawn up and over the cutting edge and folded down, as illustrated in Figure 1. The cover is then closed with the flap inserted behind the front wall of the box. The two tongues 9 of the tuck are slipped through the opening 10, as illustrated in Figure 1, and thus not only hold the box closed, but press and squeeze the forward end of the paper between the flap and the front wall and thus make displacement of it practically impossible.

When the housewife receives this package it is immediately obvious to her how the paper is to be withdrawn and all that she has to do is to remove the tuck, tear out the scored section

of card-board 11 in the cover and withdraw from the roll any desired length of paper. After the first cutting additional paper may be withdrawn by inserting thumb and forefinger through the openings provided for that purpose, as illustrated in Figure 5.

After the tuck has been removed, there would be a tendency for the cover 4 to spring open thus necessitating its replacement before use. To overcome this objection I have cut the rear upper edge of the box, as illustrated at 12 thus weakening the card-board and producing, in effect, a flexible hinge for the cover.

I claim:

A box for dispensing roll paper comprising side walls and a cover, a cutting edge along the top of the front wall, an opening in the front wall below the cutting edge, a flap on the cover lying behind the cutting edge and forming with the front wall a guide for paper to be dispensed, a tuck cut from the flap and hinged along the upper edge thereof, tongues on the tuck extending through the opening and behind the front wall to keep the box closed, and a section of the cover immediately adjacent the tuck and of substantially the size of the opening in the front wall defined by scoring so that after removal of the tuck and the scored section of the cover, paper can be drawn upward between the front wall and the flap.

In testimony whereof I affix my signature.
NICHOLAS MARCALUS.
